ROTARY TUBE RACK

Malcolm G. Murray, Ellwood City, Pa., assignor
to National Tube Company, a corporation of
New Jersey

Application March 1, 1938, Serial No. 193,377

5 Claims. (Cl. 211—1.6)

This invention relates to a tube rack, and particularly to a rotary rack for storing tubes and the like.

It is usually the practice to store tubes between conveniently spaced posts, which are either set in the ground or fastened together at the bottom in any convenient manner to form a rack. Such means of storing tubes has proved very unsatisfactory in that, in order to gain access to the tubes at the bottom of the racks, the tubes on the top thereof would have to be removed. This unnecessary handling of the tubes consumed valuable time and oftentimes resulted in damage to the tubes, especially if the walls of the tubes were thin. The present invention eliminates this disadvantage and provides a rotary rack in which any particular group of tubes is readily and easily accessible.

It is an object of the invention to provide a rotary rack having a plurality of sections for storing tubes and the like, in which, if desired, various sizes of tubes may be stored.

It is another object of the invention to provide a rotary tube rack having a plurality of sections for storing tubes and the like in which the tubes will be retained during rotation of the rack.

It is a further object of the invention to provide a simple and inexpensive rack for storing tubular articles in which such articles can be quickly and efficiently placed or removed.

It is still another object of the present invention to provide rotary racks for storing tubular articles with at least two of them connected together so as to provide temporary storing space at least therebetween.

Various other objects and advantages of my invention will more fully appear during the course of the following specification, and will be particularly pointed out in the appended claims.

In the accompanying drawings I have shown, for the purpose of illustration, one embodiment of my invention which may be assumed in practice.

45 In these drawings:

Figure 1 is a side elevational view of the tube storing rack of my invention;

Figure 2 is a sectional view taken on line II—II of Figure 1; and,

50 Figure 3 is a sectional view taken on line III—III of Figure 2.

There is shown in the drawings the improved rotary tube rack of my invention which comprises a frame 2 having a pair of parallel spaced-apart circular track-like members 3. These cir-

cular members are spaced apart a distance slightly less than the length of the tubes to be stored therein, so that the tubes will extend through and beyond each of these members. Each of the circular tracks have a segmental opening 4 therein, the purpose of which will be explained later in the specification.

There is positioned axially of the circular members a rotatable shaft 5 having a pair of spaced-apart flanges 6 positioned thereon and keyed thereto. Each of the flanges have suitably attached thereto, preferably by means of rivets, a plurality of corresponding arms 7 extending radially therefrom. These arms form a plurality of tube receiving sections 8 therebetween around the shaft 5. The corresponding oppositely disposed arms of each set of arms are preferably held together in parallel spaced relation by means of rods 9, which are attached to the ends thereof. There is positioned next to the end 10 of each of the extending arms 7 and freely mounted on the rods 9, preferably by means of suitable bearings, flanged wheels 10 which are adapted to cooperate with the circular track 3 to guide and support the shaft 5 and the arms 7 in the frame.

One end of the shaft 5 is preferably connected to a transmission 11 which is, in turn, driven by a motor 12. There is provided on the end of the shaft of the motor preferably a brake 13 which is adapted to hold the rack in any desired position. Also, if desired, the rack can be rotated by a force, applied to the arms 7 of the rack, such as by the hook of an overhead crane. A suitable brake would then be provided, preferably 35 on shaft 5, for holding the rack in any desired position.

In use, it will be understood that an empty section 8 is moved to the top of the frame opposite the segmental openings 4 therein and filled with tubes, then the rack is rotated until the next section comes into position opposite the opening 4 in the circular track-like member 3 and likewise filled. This is repeated until the entire rack is completely filled. In the event that it is desired to remove any particular group of tubes from the rack, that section in which the tubes are stored is rotated until it is opposite the opening 4, at which time the tubes can be easily and quickly removed.

It will be noted that the circular track and supporting members 3 not only guide the rack in its rotating movement but also serve to keep the tubes in the sections after each has been filled and moved to the bottom of the rack.

55

It is desirable to have two or more of these racks connected together, such as shown in Figure 1, so as to provide a temporary storage space 14 between the racks.

5 It will be seen that, by the use of the rotary rack of this invention, tubes of various sizes can be stored therein and easily and quickly removed without disturbing any other group of tubes.

10 While I have shown and described an embodiment of my invention, it will be understood that this embodiment is merely for the purpose of illustration and description and that various other forms may be devised within the scope of my invention, as defined in the appended claims.

15 I claim:

1. A rack for storing tubes and the like comprising a frame, parallel spaced-apart circular members fixedly carried by said frame, a rotatable shaft axially positioned in the circular members 20 of said frame, two corresponding sets of arms extending radially from said shaft, said sets of arms being spaced apart substantially the same distance as said circular members and forming a plurality of tube-receiving sections therebetween 25 around said shaft, said circular members adapted to retain said tubes in said sections, and means carried by said arms adjacent the ends thereof cooperating with said circular members to rotatably support said shaft and the arms carried thereby.

30 2. A rack for storing tubes and the like comprising a frame, parallel spaced-apart circular track-like members carried by said frame, a rotatable shaft axially positioned in the circular members 35 of said frame, two corresponding sets of arms extending radially from said shaft, said sets of arms being spaced apart substantially the same distance as said circular track-like members and forming a plurality of tube-receiving 40 sections therebetween around said shaft, said track-like members adapted to retain the tubes in said sections and a wheel carried by each of said arms adjacent the ends thereof, said wheels cooperating with said track-like members to support and guide said shaft and arms carried thereby at least during rotation thereof.

45 3. A rack for storing tubes and the like comprising a pair of spaced-apart stationary circular annular track-like members with each having a corresponding segmental opening therein, a rotatable shaft axially positioned through said circular members, a plurality of members carried by and extending outwardly from said shaft to

5 a point adjacent said stationary circular members to form a plurality of tube-receiving sections therebetween around said shaft and so arranged that tubes can be removed from any particular section only when that section is positioned opposite the openings in said circular members. 10 15 20 25 30 35 40 45 50 55 60 65 70 75 80 85 90 95 100

4. A rack for storing tubes and the like comprising a pair of spaced-apart stationary circular annular members with each having a corresponding segmental opening therein, a rotatable shaft axially positioned through said circular members, and two corresponding sets of arms carried by said shaft with each of said arms extending outwardly therefrom to a point adjacent said stationary circular members, said sets of arms being spaced-apart substantially the same distance as said circular members and arranged so as to provide a plurality of tube-receiving sections therebetween around said shaft, said circular members adapted to retain the tubes in each of said sections and so arranged that tubes can be removed from any particular section only when that section is positioned opposite the openings in said circular members.

5. A rack for storing tubes and the like comprising a pair of spaced-apart stationary circular annular members with each having a corresponding segmental opening therein, a rotatable shaft axially positioned through said circular members, at least two sets of arms carried by said shaft with one of them disposed substantially opposite each of said circular members and with each of said arms extending outwardly therefrom to a point adjacent said stationary circular members, said sets of arms adapted to provide a plurality of tube-receiving sections therebetween around said shaft and being arranged so that tubes can be removed from any particular section only when that section is positioned opposite the openings in said circular members, a rod arranged between each of the oppositely disposed arms of said sets adjacent the ends thereof, and means carried by each of said rods which are adapted to cooperate with said stationary circular members to support and guide said shaft and the arms carried thereby.

MALCOLM G. MURRAY.
